(57) **CLAIM**

We claim the ornamental design for a control handle for a medical device used with an endoscope, as shown and described.

DESCRIPTION

FIG. 1 is an isometric view of the handle;
FIG. 2 is a side view of the handle;
FIG. 3 is a side view of the handle;
FIG. 4 is a bottom view of the handle;
FIG. 5 is a top view of the handle;
FIG. 6 is a front view of the handle; and,
FIG. 7 is a rear view of the handle.
